UNITED STATES PATENT OFFICE.

SAMUEL K. EPLER, OF SAN DIEGO, CALIFORNIA.

PUMP.

1,123,265.

Specification of Letters Patent.

Patented Jan. 5, 1915.

Application filed June 7, 1913. Serial No. 772,377.

To all whom it may concern:

Be it known that I, SAMUEL K. EPLER, a citizen of the United States, residing at San Diego, in the county of San Diego and State 5 of California, have invented certain new and useful Improvements in Pumps, of which the following is a specification.

My invention relates to pumps.

Among the objects of the invention are: 10 first the provision of an effective form of manually operated pump which will produce a continuous, even, and steady flow of the fluid pumped from a considerable depth; second to provide in a pump of this kind a 15 plurality of fluid lifting elements and co-operating parts which will serve to provide a continuous suction so that a continuous flow of the fluid may be had; third, the provision in a pump of this kind of a plurality of fluid lifting elements adapted to alternately produce a suction and remain inactive for this purpose, one of said elements producing a suction while the other remains inactive for this purpose; and fourth, the 20 provision in a pump of this kind when said lifting elements are in the nature of heads of a valve device such as hereinafter set forth, which enables the heads to function as above stated.

25 The invention resides in the novel arrangement and combination of the several elements or parts described hereinafter in connection with the accompanying drawings illustrating the preferred embodiment.

30 In said drawings: Figure 1 is a side elevation; Fig. 2 is a vertical sectional view; Fig. 3 is a vertical sectional view of the suction tube; and Fig. 4 is a detail perspective view of the suction operating valve 35 employed.

Throughout the views of the drawings, like reference characters designate like or similar parts.

Referring specifically to the drawings, 1 40 designates a discharge chamber having a discharge outlet 1^a, the chamber being shown in the form of a vertically disposed tube. The tube is fastened to, but out of communication with, a horizontally arranged cylinder 45 designated 2, and depending therefrom is a suction tube 3, (see Fig. 3) comprising a plurality of sections designated 4 screwed together as at 5, the lowermost section being preferably provided with any suitable form 50 of trap as at 6.

Rising from the cylinder 2 and in com-

munication therewith, are the vertically disposed suction cylinders 8 having at their upper ends removable caps 9. The ends of the cylinder 2 are projected slightly beyond 60 the cylinders 8 and there receive removable closure caps 10. Said chamber 1 and tubes 8 communicate through the medium of connecting tubes 8'. Chamber 1, cylinders 2 and 8 and one section of the suction tube 3 are 65 preferably formed as an integral part of said integral structure, and has therein a suitable vent valve as at 11'. A cross-head 12 is provided to be mounted adjacent the upper end of the cylinder and packing nuts 70 13 are adapted to screw onto the stuffing boxes 14 provided around the rod having extensible movement into and from the several cylinders.

Extending through the cross head 12, 75 chamber 1, cylinder 2, and into the suction chamber, is a hollow rod designated 15 on which is suitably fastened a suction head 16. Within the tubular rod 15 is slidably mounted a rod 17, the end of which extends 80 somewhat below the end of rod 15 and has provided thereon a suction head 18. The suction head 16 may be of any suitable construction as to draw up the water on the up stroke and to permit the passage of water 85 therethrough or past the same on the down stroke. As shown in the drawings, the suction heads 16 and 18 are made of suitable flexible material such as leather, so that their outer wall will yield inwardly on the 90 down stroke to permit the upward passage of water between the head and wall of the tube bore. At the upper end of the rod 17 is fastened a cross piece 19 as by means of a set screw 20, which cross member is likewise 95 fastened by a set screw 21 to a rod 22. To the lower end of the rod 22 and to the upper end of the tubular rod 15, are fastened cross arms 23 as by means of set screws 24 engaging the proper rods 15 and 22. On each 100 cross arm 23 is fastened as at 25, rods 26 which extend and slide through the cross head 12, stuffing box 14, caps 9, and thence into the pump cylinders 8, being provided at their ends with suitable upper suction heads 27, as are the suction heads 16 and 18, the suction heads 27 are constructed to draw up or elevate the water on the up stroke and permit the passage of the water there- 105 through, or past the same on the down stroke. To this end said heads 27 are pref- 110 erably made of flexible material, such as

leather, so as to yield similarly to the heads 16 and 18. It might be here stated that the tubular rod 15 extends through the cross head 12, the central extension thereon, and the stuffing box 14 of the discharge chamber 1. Thus it will be realized that the extensions, glands, and packing form suitable packing or stuffing boxes for the piston rods 26 and tubular rod 15.

10 In the cylinder 2 is mounted for lateral movement, a valve device adapted at times to cut off communication between tube 3 and cylinders 8, having at opposite ends, heads 28 being fastened together by means of a 15 connecting member 29, being formed intermediate its ends to provide an elongated slot 30 through which the rods 15 and 17 pass, as best seen in Fig. 2. Within the chamber 2 is preferably provided, interiorly extending 20 annular flanges 31 which form abutments to limit the sliding movement of the heads 28.

Fastened to the cross head 12 are the arms 32 of an inverted V-shaped bracket to which 25 is pivoted at its upper end on a pivot member 33, an operating lever or handle designated 34. The lever 34 has adjustably fastened thereto, clamp blocks 35 as by means of the set screws 36, to which blocks are pivoted at 37, pitman rods 38 also pivoted as at 39 to the cross arms 23.

In operation, the operating lever 34 is rocked or moved vertically through manual engagement, which action causes the alternate raising and lowering of the suction heads 27 and suction heads 16 and 18, it being clear that the pitman 38 of one cross bar 23, effects the movement of the rod 17 through its connection thereto by means of 40 the rod 22 and connecting member 19. The other pitman 38 by means of the other cross arm 23, causes the shifting of the tubular rod 15 and suction head 16 carried thereby, and which latter arm 23 also causes movement of the other piston 27 through its connection thereto by means of its rod 26. As 45 one set of connected upper and lower suction heads move simultaneously upwardly, the other set of connected upper and lower 50 suction heads move simultaneously downwardly, the flexible construction of the heads 16 and 18 and 27 permitting the water to act against the same and contract them so that the water may gush or flow upwardly 55 around the same. Thus while one set of upper suction heads and lower suction heads is on the up stroke creating a suction through the pump and lifting the water, the other set of upper suction heads and lower 60 suction heads are on their down stroke. This action is alternate. By means of this arrangement there is always a suction in the pump which causes a continuous and even flow of water to pass through tube 3, 65 cylinders 2 and 8, tubes 8', chamber 1, and

from the same through the opening at 1^a. When one of the heads 27 moves upwardly on its up stroke and creates a suction through the pump, the valve device having the heads 28, is shifted longitudinally so that the head 28 adjacent the other cylinder, will cut off all communication therewith. Upon the down stroke of this same upper suction head the other upper suction head will start to move upwardly which will thus draw the 75 adjacent head 28 away from its seat or flange 31, to permit the proper suction through the pump. While the heads 27 descend, the valve heads 28 are in such position as to close communication between the 80 proper chambers 8 and tube 3, whereby the water pumped into the tubes 8 is prevented from back-flow into tube 3. Likewise the construction of the heads 17 and 18 prevent the return of backflow of the water after being pumped past the same into tube 3.

I claim—

1. In a pump, a pair of suction cylinders, a third cylinder mounted to be connected with said cylinders, a suction head in each of said first cylinders, suction heads in said third cylinder, and means to actuate the head in said pair of cylinders alternately in opposite directions and to simultaneously operate the suction heads in said third cylinder.

2. In a pump, suction cylinders, suction heads mounted in said cylinders, a suction tube connected with said cylinders, suction heads mounted in the suction tube, and operating means to simultaneously cause movement of the suction head in one of said suction cylinders and one of the suction heads mounted in the suction tube.

3. In a pump, a pair of suction cylinders, a suction tube connected with each of said cylinders, suction heads mounted in said suction cylinders to be capable of reciprocatory movement, a pair of suction heads slidably mounted in said suction tube, means to transmit motion simultaneously to one of the suction heads in the suction tube and to the suction head of one of said suction cylinders simultaneously and to cause opposite movement of the remaining like parts.

4. In a pump, a pair of suction cylinders, a suction tube connected with each of said cylinders, suction heads mounted in said suction cylinders to be capable of reciprocatory movement, a pair of suction heads slidably mounted in said suction tube, means to transmit motion to one of the suction heads in the suction tube and to the suction head of one of said suction cylinders simultaneously and to cause opposite movement of the remaining like parts, and means operable by the creation of suction to establish communication between said tube and said cylinders one at a time.

5. In a pump, a pair of suction cylinders,

suction heads mounted to be capable of reciprocatory movement simultaneously and in opposite directions in said cylinders, a suction tube, suction heads mounted in said 5 suction tube to have movement upon the actuation of the suction heads within said cylinders, and a valve shiftable to cut off communication between said cylinders.

6. In a pump, a pair of suction cylinders, 10 suction heads mounted in said cylinders to be simultaneously movable and to reciprocate in opposite directions, a suction tube, a pair of suction heads mounted in said suction tube, a connection between the suction 15 head in each of said cylinders and one of the heads in said suction tube, and all of said parts so arranged that one of the suction heads in said suction tube and the suction head of one of said cylinders are 20 positively actuated in the same relative movement and simultaneously the remaining like parts are operated in an opposite reciprocatory path.

7. In a pump, a pair of suction cylinders, 25 suction heads mounted in said cylinders to be simultaneously movable and to reciprocate in opposite directions, a suction tube, a pair of suction heads mounted in said suction tube, a connection between the suction 30 head in each of said cylinders and one of the heads in said suction tube, all of said parts so arranged that one of the suction heads in said cylinders is positively actuated in the same relative movement and simultaneously the remaining like parts are operated in an opposite reciprocatory path, and a suction actuated valve to cut off communication alternately between said cylinders as the suction heads are operated.

40 8. In a pump, first and second suction cylinders, suction heads in said cylinders, a third cylinder in communication with said cylinders, a valve device in said third cylinder, a suction tube in communication with said 45 third cylinder, suction heads in said suction tube to be operated simultaneously with the operation of the suction heads in said cylinders, and fluid discharge means from said suction cylinders.

50 9. In a pump, first and second suction cylinders, suction heads in said cylinders, a third cylinder in communication with said cylinders, a slidable valve device in said third cylinder provided with a head at opposite ends, a suction tube in communication with said third cylinder, suction heads in said suction tube connected to be operated simultaneously with the operation of the suction heads mounted in said cylinders, 55 and fluid discharge means leading from said suction cylinders.

60 10. In a pump, first and second cylinders, suction heads in said cylinders, a third cylinder in communication with said cylinders, 65 a suction tube in communication with said

third cylinder, a first and second suction head mounted in said suction tube, connections formed between said suction tube and the suction heads in said first and second cylinders in such a manner that the operation of the suction heads in the cylinders 70 causes simultaneous movement of the suction heads within said suction tube, a suction actuated valve device in said third cylinder movable to alternately cut off and establish communication between said tube and said first and second cylinders, and fluid discharge means leading from said suction cylinders.

75 11. In a pump, first and second cylinders, suction heads in said cylinders, a third cylinder in communication with said cylinders, a suction tube in communication with said third cylinder, fluid discharge means for said suction cylinders, a suction device extending into said tube having a rod extending through said third cylinder, a slidable valve device mounted in said third cylinder, said valve device provided with an elongated slot through which said rod extends.

80 12. In a pump, first and second suction cylinders, first and second suction devices in said cylinders, a suction tube, a suction device in said tube, and operating means arranged to cause reciprocatory movement of the suction devices in said cylinders and the suction device mounted in the suction tube 90 simultaneously in opposite directions.

85 13. In a pump, first and second suction cylinders, suction heads mounted in said cylinder to be capable of reciprocatory movement, a suction tube, a hollow rod, a rod slidably received within said hollow rod, suction heads connected with each of said rods and mounted in said suction tube, 100 and a connection between each of said rods and said cylinder suction heads arranged in such a manner that said parts are operated simultaneously.

105 14. In a pump, first and second suction cylinders, suction heads mounted in said cylinder to be capable of reciprocatory movement, a suction tube, a hollow rod, a rod slidably received within said hollow rod, suction heads connected with each of said rods and mounted in said suction tube, 110 a connection between each of said rods and said cylinder suction heads arranged in such a manner that said parts are operated simultaneously, and means to cause a simultaneous reciprocatory movement of said rods in opposite directions and to consequently impart a like motion to said suction heads connected in pairs with said rods.

115 15. In a pump, first and second suction cylinders, suction devices in said cylinders, a suction tube, suction devices in said tube having rods, arms, means to connect said arms to said devices and said rods, a lever, and means to connect said arms to said lever.

16. In a pump, first and second suction cylinders, suction devices in said cylinders, a third cylinder in communication with said cylinders, a suction tube in communication with said third cylinder, fluid discharge means for said suction cylinders, a valve mounted in said third cylinder, suction devices in said tube having rods, arms connecting said rods to said first devices and means to actuate said arms and accordingly said first and second suction devices.
17. In a pump, first and second suction cylinders, a third cylinder in communication therewith, a valve device in said third cylinder, a suction tube in communication with said third cylinder, fluid discharge means from said suction cylinders, suction devices mounted in said first and second cylinders, suction devices in said suction tube each provided with a rod, arms, means to fasten said arms to said rod and said pistons, a lever, means to mount said lever, and pitmen connecting said lever and said arms.
18. In a pump, first and second suction cylinder members, a third cylinder in communication with said cylinders, a discharge

chamber member in communication with said suction cylinders, a valve device for said third cylinder, a cross head, means to mount said cross head from one of said members, suction heads in said first and second cylinders provided with rods slidably mounted in said cross head, suction heads mounted in said suction tube each provided with a rod, one of said latter rods slidably mounted through said cross head, discharge chamber, third chamber and suction tube, and another of said latter rods mounted through the other, an arm connecting one of said first rods to one of said latter rods, a second arm connected to the other of said first rods, a rod connected to said arm, a connecting member joining said last rod and one of said suction rods, a bracket mounted on said cross head, a lever pivoted to said bracket, and pitmen connecting said lever to said arms.

In testimony whereof I affix my signature in presence of two witnesses.

SAMUEL K. EPLER.
